UNITED STATES PATENT OFFICE

WILLIAM F. HAAS, OF ROCKAWAY, NEW YORK

DESIGN FOR A BUCKLE

Application filed June 6, 1932. Serial No. 44,004. Term of patent 3½ years.

To all whom it may concern:

Be it known that I, WILLIAM F. HAAS, a citizen of the United States, residing at Rockaway, L. I., in the county of Queens and State of New York, have invented a new, original, and ornamental Design for a Buckle, of which the following is a specification, reference being had to the accompanying drawing, forming part thereof.

Fig. 1 is a plan view of a buckle showing my new design.

Fig. 2 is a side view thereof.

I claim:

The ornamental design for a buckle as shown.

WILLIAM F. HAAS.
